US0D1112901S

(12) **United States Design Patent** (10) **Patent No.:** **US D1,112,901 S**
(45) **Date of Patent:** **** Feb. 10, 2026**

- (54) **MOTION SENSOR NIGHT LIGHT**
(71) Applicant: **Bo Wang**, Guangdong (CN)
(72) Inventor: **Bo Wang**, Guangdong (CN)
(**) Term: **15 Years**
(21) Appl. No.: **29/952,544**
(22) Filed: **Jul. 16, 2024**
(51) LOC (15) Cl. **26-05**
(52) U.S. Cl. **USPC D26/85; D26/108; D26/89**
(58) **Field of Classification Search**
USPC ... D26/72, 81, 85, 89, 91, 93, 104, 106, 108
CPC F21S 8/033; F21S 9/037; F21W 2121/004;

(57) **CLAIM**

The ornamental design for a motion sensor night light as shown and described.

DESCRIPTION

FIG. 1 is a front, right, and top perspective view of a motion sensor night light, showing my new design;

FIG. 2 is a rear, left, and bottom perspective view thereof;

FIG. 3 is a front elevational view thereof;

FIG. 4 is a rear elevational view thereof;

FIG. 5 is a left elevational view thereof;

FIG. 6 is a right elevational view thereof;

FIG. 7 is a top plan view thereof; and,

FIG. 8 is a bottom plan view thereof.

The broken lines in the drawings depict portions of the motion sensor night light that form no part of the claimed design.

1 Claim, 8 Drawing Sheets
